DESIGN FOR A CHAIR

Wilton C. Dinges, Baltimore, Md., assignor to
Emeco Corporation, Baltimore, Md., a corpora-
tion of Maryland

Application September 11, 1946, Serial No. 133,240

Term of patent 3½ years

(Cl. D15—1)

To all whom it may concern:

Be it known that I, Wilton C. Dinges, a citizen of the United States, residing at Baltimore, Maryland, have invented a new, original, and ornamental Design for a Chair, of which the following is a specification, reference being had to the accompanying drawing, forming a part thereof.

In the accompanying drawing:

Figure 1 is a perspective view of a chair showing my new design,

Figure 2 is a rear elevation thereof, and

Figure 3 is a side view thereof.

The characteristic feature of my design resides

in the specific configuration of the upright back supporting members.

I claim:

The ornamental design for a chair, as shown and described.

WILTON C. DINGES.
